(57) **CLAIM**

The ornamental design for a sauna vest with belt, as shown and described.

DESCRIPTION

FIG. 1 is a top front perspective view of the sauna vest with belt showing my new design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top elevation view thereof;

FIG. 7 is a bottom elevation view thereof; and,

FIG. 8 is a top front perspective view thereof, with the belt shown in the open position.

The broken lines shown in the drawings illustrate portions of the sauna vest with belt that form no part of the claimed design.
